JAMES H. DOWNEY, OF GAINESVILLE, GEORGIA.

HOISTING DEVICE.

No. 852,877.

Specification of Letters Patent.

Patented May 7, 1907.

Application filed June 15, 1906. Serial No. 321,939.

To all whom it may concern:

Be it known that I, JAMES H. DOWNEY, a citizen of the United States, residing at Gainesville, in the county of Hall and State of Georgia, have invented a new and useful Hoisting Device, of which the following is a specification.

This invention relates to hoisting devices such as are used particularly for raising telegraph poles into position, although the device of this invention can of course be used for other purposes whenever desired.

The operation of raising telegraph poles into upright position is usually attended with considerable difficulty by reason of the fact that it is necessary to employ a lofty framework or tripod which is usually at least one-half as high as the telegraph pole and is therefore extremely cumbersome in construction and difficult to move from place to place each time a new pole is to be planted.

The object of the present invention is to provide an extremely simple, strong, durable, inexpensive and compact device which can be readily transported from place to place as well as easily placed in proper position, and which is adapted in a thoroughly practical manner to raise a telegraph pole or the like into position to be properly planted in the ground.

With the foregoing and other objects in view, which will appear as the description proceeds, the invention resides in the combination and arrangement of parts and in the details of construction hereinafter described and claimed, it being understood that changes in the precise embodiment of invention herein disclosed can be made within the scope of the following claims without departing from the spirit of the invention or sacrificing any of its advantages.

In the accompanying drawings forming part of this specification: Figure 1 is a side elevation of a hoisting device constructed in accordance with the present invention, in the act of raising a pole. Fig. 2 is a vertical section through the support of the hoisting device. Fig. 3 is a horizontal section through the pushing member above the support, which is shown in plan. Fig. 4 is a front elevation of the pushing member. Fig. 5 is a longitudinal section and Fig. 6 is an enlarged section through the pushing member at a right angle to Fig. 5.

Like reference numerals indicate corresponding parts in the different figures of the drawings.

The improved hoisting device of this invention preferably comprises a self-supporting flexible pushing member A which, while it may be of any suitable construction, preferably is formed of a plurality of rigid sections 1 which are pivotally connected with each other, as indicated at 2, so that they can flex or bend slightly in one direction and can be folded upon each other in the opposite direction. While the sections 1 may be of any suitable form and construction, said sections preferably consist of angle-irons a which are separated from each other by filling pieces b and are held in assembled position by bolts or other suitable devices c.

As shown in the drawing, each of the flanges of the angle-irons a which fit against the opposite sides of the filling pieces b, is formed at one end with a perforated ear or extension d through which the bolt or pivot member 2 extends, the ears or extensions d of one section being fitted between the inner flanges of the adjacent section on opposite sides of the filling piece b which is suitably cut away at its ends to provide narrow cavities to receive the ears d. Each of the filling pieces b projects forward beyond the ends of the angle-irons a into the space between the perforated ears d, so that when the rigid sections are in extended position, the filling piece of one section will project for a certain distance in between the angle-irons of the next adjacent section, as shown, whereby to brace the sections with respect to each other and thus prevent lateral bending of the pushing member A when in extended position. It will be obvious that the sections 1 can be folded in a forward direction upon each other, and that backward flexing of the sections 1 with respect to each other is prevented by the filling pieces b which contact with each other at their ends. In some cases it is desirable that the pushing member A should be permitted to flex backward to a limited extent. I prefer to arrange for this limited backward flexing of the pushing member A by forming each of the filling pieces b and angle-irons a with slightly beveled ends, as indicated at e, so that when all the rigid sections 1 are extended in such manner that the beveled ends of the different

filling pieces are pressed together, the pushing member A, as a whole, will be permitted to flex backward on a slight curve, as indicated, whereby the endwise or longitudinal pressure on the pushing member A serves to press the different sections firmly together and produce a locking action which will prevent them from accidentally breaking joints with each other.

10 While the filling pieces b of the self-supporting flexible pushing member A, with their beveled ends which permit a slight backward flexing of the member A as described, constitute one convenient means of locking the sections 1 in extended position, still in some cases it is preferable to employ positively acting means for automatically locking the sections of the member A in extended position. The automatic locking 15 means which I prefer to use consists of a plurality of resilient catches 3 having beveled heads 4. Each of the resilient catches 3 is mounted on one of the angle-irons a in such manner that when the sections are 20 moved into extended position, the beveled head 4 will overlap the next iron a and extend slightly outward therefrom through an opening 6. It will be obvious that the resilient catches 3 will act to hold the sections 1 securely in alignment with each other and thus 25 prevent them from folding accidentally upon each other or breaking joints.

The support for the pushing member A is indicated generally by B and consists of a 30 suitable body portion 10 provided with diverging legs 11. The body portion 10 preferably consists of a U-shaped piece of metal forming a channel 14 through which the flexible pushing member A slidably extends.

40 The operating mechanism for moving the flexible pushing member A upward through the channel 14 of the support B preferably comprises an operating lever 20 which is pivotally mounted between the open ends of the 45 U-shaped body portion 10, as indicated at 21, and is provided at its inner end with a hinged member 22 having a notched portion 23 adapted to engage one of the bolts c which extend across the front face of the rigid sections 1 of the pushing member A and form 50 rack members, as shown. The operating mechanism for the pushing member A, also includes a pawl 24 which is pivotally mounted at 25 in the support B and is formed at its 55 upper free end with a notch 26 adapted to engage one of the bolts or rack members c on the adjacent section of the pushing member A. It will be obvious that when the outer end of the operating lever 20 is depressed, the 60 hinged member 22 will move the pushing member A upward. During the upward movement of the pushing member A the pawl 24 rides over the rack members c, and finally engages one of said members so as to hold the 65 pushing member in raised position during the

time that the operating lever 20 is being moved to raised position for another stroke.

During the operation of pushing the telegraph pole C upward into position to be planted, said pole of course moves gradually 70 from an approximately horizontal position to an approximately vertical position, the end of said pole which remains on the ground serving as a fulcrum point on which the pole moves. As the telegraph pole gradually 75 changes its angle of inclination with respect to the ground, it is desirable that the support B should be adjusted in such manner as to change its angle of inclination and thus cause the pushing member A to maintain a proper 80 position with respect to the pole. The means which I provide for adjusting the position of the support B, consists preferably in pivotally connecting the forward pair of legs 11 with the support B, as indicated at 30, and in 85 mounting between the upper ends of said legs a pivotal plate 31 through which extends an adjusting screw 32 having its rear end suitably swiveled at 33 upon an arm 34 depending from the support B and rigidly connected 90 therewith in any suitable manner. In some cases, where the device is being used upon soft ground, the adjustable pair of legs 11 can be provided, if desired, at their lower ends with shoes 35 so that they will slide over the 95 surface of the ground toward the rigid set of legs when the adjusting screw 32 is manipulated, the rigid set of legs being preferably provided with lower ends which are sharp enough to bite into the ground and thus prevent the entire support from slipping. When 100 the movable pair of legs 11 are adjusted toward the rigid legs, the angle of inclination of the support B is gradually changed so as to cause the flexible pushing member A to preserve a proper position with respect to the pole C as it is raised into vertical position. At its upper end, the pushing member A is provided with any suitable form of engaging 105 device D adapted to embrace the pole C and hold it in position, the engaging device which is preferred to use consisting of an approximately semi-circular saddle piece connected 110 with the upper section 1 of the member A and fitting under the pole C, as shown.

115 It is a minor object of the present invention to provide an auxiliary elevating device for initially elevating the pole C a sufficient distance above the ground to permit it to be fitted into the saddle piece or engaging device D. The preferred auxiliary elevating device, which is indicated generally by E, consists of a rod 40 which is mounted for vertical sliding movement in the brackets 41 mounted upon the support B. The rod 40 120 preferably is provided with an adjustable collar 42 provided with a screw 43 by means of which it can be secured against movement on the rod 40 so as to hold the same properly in elevated position and at the same time per- 125 130

mit said rod 40 to be rotated whenever necessary. The upper end of the rod 40 is hooked or bent, as shown at 44, and is provided with a pulley 45 through which extends a flexible element 46 provided at its end with a hook 47 by means of which the flexible element can be passed around the pole C to form a loop for elevating said pole. The opposite end of the flexible element 46 5 extends around a drum 48 on the support B, said drum being provided with a gear element 49 which is operated by a gear wheel 50 having a crank handle 51, accidental rearward movement of the gear element 49 being prevented by a pawl 52. In operating the improved device, the auxiliary elevating device E is employed for lifting the pole high enough to fit it into the engaging device D when the flexible pushing member A is in its 10 lowest position.

As shown in the drawing, the self-supporting flexible pushing member A is preferably constructed so that the curve which it will form when flexed slightly backward, will 15 form a segment of a circle having for its center the lower end of the telegraph pole C; that is, the end which rests upon the ground. For this reason, when the support B has been 20 properly adjusted so that it will move the pushing member upward on the segment of a circle having the bottom of the pole for its center as described, it will be unnecessary to change the inclination of the support B during 25 the whole time that the pole is being raised to elevated position, as, of course, the portion of the pushing member A which is moving out of the upper end of the support B will always maintain the same angle with respect to said support B irrespective of the 30 position of the pole.

When the operation of raising the pole is first begun, the flexible pushing member A is disposed along the surface of the ground in front of the support B and with its end 35 extending upward through said support. As the operating mechanism, including the lever 20, is actuated, the pushing member is moved upward thus dragging its forward end slowly toward the support B. When 40 the pole has been completely raised and properly planted the pawl 24 and the hinged member 22 are moved out of engagement with the pushing member and said member is drawn slowly downward through the support 45 B, this operation being accomplished by a workman grasping the lower end of the flexible pushing member and drawing it along the ground so that it will slide downward through the supporting member.

In order to facilitate the downward movement of the flexible pushing member A, I provide automatic means for unlocking the 50 resilient catches 3 which in one form of the invention are used for locking the sections 1 together. The preferred means for unlock-

ing the sections consists of a wiping member 60 which is mounted beneath the support B in such manner that the sections 1 of the member A will scrape or move thereover so that the beveled heads 4 will be pushed rearward into the openings 6 so as to permit the flexible member A to bend and be drawn along the ground in a forward direction away from the support B. The wiping member 60 preferably is in the nature of a curved bar of 55 metal which is suitably secured to the supporting member B at its upper end and is tapered as shown in Fig. 2, so that as the flexible pushing member is drawn downward through the supporting member B in the 60 manner described, the projecting ends 4 of the resilient catches 3 will wipe over said member 60 and be thereby pushed backward so as to become disengaged from the perforations 6 and thus unlock the different sections 65 of the flexible member.

The improved device of this invention is strong, simple, durable and inexpensive in construction as well as thoroughly efficient in operation. It can be carried readily from 70 point to point and easily and quickly arranged in operative position. Its use avoids the necessity of constructing lofty tripods for raising the telegraph pole into position. Furthermore, it avoids the danger and expense of using 75 spiked pushing poles which are sometimes employed by a gang of men in raising a pole to proper position.

If at any time the pivotal connections between the sections 1 of the flexible pushing 80 member should become slightly worn so as to permit a small amount of lateral movement, whereby the telegraph pole might be permitted to swing to one side or the other, it would be advisable to employ two of the 85 improved hoisting devices of this invention, the two devices being separated from each other to a slight extent and having their two 90 flexible pushing members converging upward to the pole.

It will be understood, of course, that the pole which is being raised into position can be steadied with suitable guide ropes which may be attached to the pole and held by men at their lower ends so as to prevent lateral swinging of the pole. Ordinarily, however, the guide ropes can be dispensed with.

What is claimed as new is:

1. A hoisting device having a curved self-supporting flexible pushing member.
2. A hoisting device having a curved self-supporting flexible pushing member comprising a plurality of pivotally connected sections.
3. A hoisting device having a curved self-supporting flexible pushing member comprising a plurality of pivotally connected sections and means for automatically holding said sections in extended position.
4. A hoisting device having a self-support-

ing flexible pushing member adapted to fold in one direction and to flex slightly in the opposite direction.

5. A hoisting device having a flexible pushing member comprising a plurality of pivotally connected sections provided with resilient catches for locking the same in extended position.

6. A hoisting device having a curved flexible pushing member, operating mechanism for moving said pushing member longitudinally, and means for automatically locking said pushing member in extended position.

7. A hoisting device having a flexible pushing member comprising a plurality of pivotally connected sections, means for automatically locking the said sections together in extended position, means for moving said pushing member longitudinally, and automatic means for unlocking the sections of said pushing member.

8. A hoisting device comprising a support, means for adjusting the position of the support, a flexible pushing member extending through the support, said member being adapted to flex backward when in extended position and operating mechanism carried by the support for moving the pushing member longitudinally.

9. A hoisting device comprising a support having a plurality of rigid legs and a plurality of adjustable legs, a flexible pushing member extending through said support, and operating mechanism for moving said pushing member longitudinally in said support.

10. A hoisting device comprising a support, an auxiliary elevating device mounted upon said support, a flexible pushing member extending through said support, and means for moving said pushing member longitudinally through the support.

11. A pole hoisting device comprising a

support, a flexible pushing member extending through said support and having a pole engaging device at its upper end, said pushing member being adapted to flex backward on the segment of a circle having the lower end of the pole for its center, and means carried by the support for moving the pushing member upward.

12. A hoisting device comprising a support, a pushing member comprising a plurality of pivotally connected sections having beveled ends, so as to be adapted to flex backward when in extended position and operating mechanism carried by the support for moving the pushing member.

13. A pole hoisting device comprising a support having a pair of rigid legs, a pair of pivotal legs having shoes on their lower ends, an adjusting screw for changing the position of the pivotal legs, an operating lever mounted on said support and having a hinged member, a pushing member comprising a plurality of pivotally connected sections having beveled ends and transversely extending rack members, said pushing member extending upward through said support, resilient catches carried by the sections of said pushing member for automatically locking the same in extended position, a saddle piece connected with the upper end of said pushing member, a cam member mounted underneath said support and adapted to engage said resilient catches for unlocking the sections of the pushing member, and an auxiliary elevating device carried by said support.

In testimony that I claim the foregoing as my own, I have hereto affixed my signature in the presence of two witnesses.

JAMES H. DOWNEY.
